J. J. MANDERSCHEID

POLISHING WHEEL

Filed Dec. 13, 1922

Inventor:
James J. Manderscheid
By Chas. S. Gilman
Atty.

UNITED STATES PATENT OFFICE.

JAMES J. MANDERSCHEID, OF NORWOOD PARK, ILLINOIS, ASSIGNOR TO ADVANCE WHEEL MANUFACTURING COMPANY, OF CHICAGO, ILLINOIS, A CORPORATION OF ILLINOIS.

POLISHING WHEEL.

Application filed December 13, 1922. Serial No. 606,696.

To all whom it may concern:

Be it known that I, JAMES J. MANDERSCHEID, a citizen of the United States, residing at Norwood Park, in the county of Cook

5 and State of Illinois, have invented certain new and useful Improvements in Polishing Wheels, of which the following is a specification.

This invention relates, generally, to improvements in polishing wheels, but particularly to that type of such wheels which are made up of superposed layers or disks of canvas, sheep-skin, walrus hide, wood and the like, and it consists in certain 15 peculiarities of the construction, novel arrangement and combination of the various parts thereof, as well as, in the novel method of making the same, as will be hereinafter more fully set forth and specifically claimed.

20 The principal object of the invention is the provision of polishing wheels of the highest efficiency designed, more particularly, for polishing castings of various, and of such structural character, that certain 25 of the layers or disks of the wheel can be made up of parts, of the desired material, which have heretofore usually been discarded as useless, thereby effecting great economy in material and consequently in the manufacture of the wheels.

Another and important object of the invention is to so construct, arrange and unite together, the various parts of the wheel as to render the liability of breakage, or flying 35 apart of portions of the wheel, due to centrifugal action or strain incident to the high speed at which such wheels are rotated, impossible or reduced to a minimum.

A further object is, to furnish means for 40 interlocking the adjacent edges of the segments or sectors of the sectional disks of the wheel, in such a way as to absolutely prevent their accidental detachment or dislocation one from another, or in other words, 45 to render the sectional disks as strong and durable as if they were each made of a single piece of material.

The invention also contemplates new features or steps in the method of preparing 50 and assembling parts of the wheel.

In the accompanying drawing,—

Fig. 1 is a view in side elevation of a polishing wheel illustrating the preferred embodiment of the invention.

Fig. 2 is a central sectional view taken 55 on line 2—2 of Fig. 1 looking in the direction indicated by the arrows.

Fig. 3 is a detached perspective view of one of the segments which go to make up or form one of the sectional disks of the 60 wheel.

Fig. 4 is a face view of a portion of one of said segments, illustrating a modification in the form of the recesses used for receiving interlocking tongues or projections on 65 the edge of the adjacent segment.

Fig. 5 is an enlarged sectional view of a portion of one of the disks or layers of the wheel, taken on line 5—5 of Fig. 4 showing it in about the condition it will 70 appear after having been treated to a liquid solution for giving rigidity to the material out of which the segment is made.

Fig. 6 is an enlarged edge view of one 75 of the segments showing the formation and disposition of the recesses therein for the reception of interlocking tongues or projections on the edge of the adjacent segment or section, and

Fig. 7 is a perspective view of portions of 80 a pair of the segmental sections showing them in the initial positions they will occupy when they are being secured together.

Corresponding numerals of reference refer to like parts throughout the different 85 views of the drawing.

As is clearly shown in Fig. 2 of the drawing, the wheel comprises a plurality of superposed layers or disks 8 and 9, alternately arranged, and having a central opening 10^a 90 for the reception of a shaft on which the wheel is mounted for rotation. These disks may be made of any suitable material, such as tough leather, canvas, sheep skin, walrus hide, wood, and the like, and of any suitable 95 dimensions. The disks 8 are each formed of a single piece of material, while each of the disks 9 comprises a plurality of segmental sections 10 of uniform thickness. Each of the sections 10 is provided in one of 100

its edges with one or more recesses 11, and at its opposite edge with one or more tongues or projections 12 corresponding in shape and size to the shape and size of said recesses. By this arrangement it is apparent that by placing the tongues 12 of one of the sections of the composite disk in the recesses of the adjacent edge of the section or segment adjoining the said sections will be interlocked so as to prevent outward radial displacement no matter what the form of the recesses and projections may be.

However, in order to not only lock the sections together against outward radial displacement, but also against lateral movement in either direction, I prefer to provide each of the segments 10 in one of its straight edges, with a plurality of recesses 11, which recesses have their walls beveled in opposite directions alternately, as is clearly shown in Fig. 6 of the drawings. The other edge of the section is provided with a plurality of tongues or projections 12, which have their walls beveled in opposite directions alternately and made of a size to fit snugly in the recesses of the adjacent segment. By this arrangement it is manifest that the segments will be interlocked against lateral movement as well as outward radial movement.

As the segments 10, as well as the one piece disks 8 are by preference made of leather or material possessing some flexibility and of an absorbent character, it is desirable that the edge portions of the segments 10 in which the recesses are formed and on which the interlocking tongues or projections therefor are provided, shall be substantially stiff or rigid, in order to permanently maintain the segments in their interlocked positions, a coating 13 of any suitable material or solution which will quickly permeate the material of the segments, readily dry thereon and give rigidity and stability thereto is applied to said edges, recesses and tongues.

The application of the coating 13 to the edges of each of the segments 10 is preferably made before the said segments or sections are united, but it is obvious that the segments may first be united and then the coating applied thereto without a departure from the spirit of the invention. The material or solution providing the coating 13 may or may not have adhesive qualities.

In uniting the segments or sections 10 to form a complete disk, the members of a pair of the segments are placed with their straight edges, one of said edges having the projections 12 or tongues, and the other the recesses 11, diagonally with respect to each other and in contact with one another as shown in Fig. 7 of the drawing. When in this position one of the tongues or projections 12 will be located on one side of the

segments 10 having the recesses 11 therein, while the other projection or tongue 12 will be on the opposite side of the recessed segment. Now, by aligning the faces of the segment 10, it is manifest that the projections or tongues 12 will enter the recesses from opposite sides, thus firmly securing the segments together. After the sectional disks have thus been formed, said sectional disks and the one piece disks 8 are coated with glue which will penetrate the material out of which the disks are made, and the disks are then placed one on the other so that the one piece disks 8 and the sectional disks 9 will be alternately arranged and so that the openings of said disk will register with one another as is clearly shown in Fig. 2 of the drawings, in which view it will be understood that a single piece disk 8 is located outwardly on each face of the wheel. The assembled disks are now placed in a press and subjected to pressure for a sufficient time to permit the glue to become dry when the wheel is ready for use.

In Fig. 4 of the drawing is shown a modification in the construction of the recesses in one of the edges of each of the segments composing the sectional disks. In this modified form the recesses 11^a are circular in shape instead of being of dove tail shape, as shown in other views of the drawing. When this modified form of the recesses is employed, it is manifest that the projections for engagement therewith and located on the adjacent segment, are of a corresponding shape to said recesses. The modified form of recesses may have their walls tapered in opposite directions as shown in Fig. 6 and above described.

Having thus fully described my invention, what I claim as new and desire to secure by Letters Patent is—

1. A segmental section for polishing wheels having its periphery curved in the arc of a circle, its sides flat, and one of its edges provided with recesses to receive and engage correspondingly shaped projections on the edge of an adjacent section, the other edge being provided with interlocking projections for engagement with recesses in the edge of a section adjacent thereto, the edges of the sections including the recesses therein and the projections thereon having applied thereto absorbent material for giving rigidity or stiffness to said parts.

2. The herein described method of constructing a polishing wheel composed of a plurality of superposed disks, consisting in making one of said disks of separated segmental sections, each of said sections having one of its straight edges provided with a plurality of oppositely flared recesses and the other straight edge of each section being provided with interlocking projections enlarged in opposite directions,

coating the straight edges including their recesses and projections with material for giving stiffness and rigidity to said parts, then placing the projection carrying edge 5 of one of the sections diagonally with respect to the recess carrying edge of another section and against the same and then placing said sections in alignment and at the same time fitting the projections on one 10 section into the recesses of the other section.

3. A section for polishing wheels having one of its edges curved in the arc of a circle, its sides flat, and one of its edges 15 provided with recesses therein to receive and engage correspondingly shaped pro-

jections on the edge of an adjacent section, the edge of the section including the recesses therein having applied thereto absorbent material for giving rigidity or 20 stiffness to said parts.

4. A section for polishing wheels having one of its edges curved in the arc of a circle, its sides flat, and one of its edges provided with interlocking projections adapted 25 to engage correspondingly shaped recesses on the edge of an adjacent section, the edge of the section including the said projections having applied thereto absorbent material for giving rigidity or stiffness to said parts.

JAMES J. MANDERSCHEID.
